W. W. Martin

United States Patent Office.

WILLIAM W. MARTIN, OF ALLEGHENY CITY, PENNSYLVANIA.

Letters Patent No. 73,621, dated January 21, 1868.

IMPROVEMENT IN LUBRICATING CAR-WHEELS.

The Schedule referred to in these Letters Patent and making part of the same.

TO ALL WHOM IT MAY CONCERN:

Be it known that I, WILLIAM W. MARTIN, of the city and county of Allegheny, in the State of Pennsylvania, have invented a new and useful Improvement in "Lubricating Car-Wheels;" and I do hereby declare that the following is a full and exact description thereof, reference being had to the accompanying drawings, and to the letters and figures of reference marked thereon.

The nature of my invention consists in providing the interior of a car-wheel with an oil-reservoir, which communicates with an oil-chamber in the opening for the axle, said reservoir and oil-chamber being so constructed and arranged with relation to each other that the oil will be supplied to the axle of the wheel in limited quantities, in the manner hereinafter described.

To enable others skilled in the art to make and use my invention, I will proceed to describe its construction and operation. In the accompanying drawings, which form part of my specification—

Figure 1 is a front elevation of a car-wheel.

Figure 2 is a transverse section of the same, cut through at line *x* of fig. 1, and represents the oil-reservoir and its relation to the oil-chamber in the opening for the axle.

Figure 3 represents a section of the wheel when cut through at line *x'* of fig. 2.

I construct the car-wheel in any of the known forms, and by the ordinary means. In the interior of the wheel, near the opening *B* for the axle, I core out a reservoir, *A*, for oil, or other lubricating-material. The reservoir *A* is made in the form represented in the drawings, but may be made in any desired form, but in every case must be provided with a projection, *O*, extending into the reservoir *A*, and through this projection must be an opening, *3*, communicating between the oil-reservoir *A* and the oil-chamber *n* in the opening *B* for the axle.

As the form of the reservoir *A* and oil-chamber *n*, and their relation to the opening for the axle, will be readily seen by reference to the accompanying drawings, and as the means for and the manner of coring out such reservoir, chamber, or cavity in a wheel or other casting is a thing well known and understood by the skillful moulder and mechanic, I will, therefore, without further description of the construction of my improvement, proceed to describe its operation, which is as follows:

I fill the reservoir up to about the line *4* with oil, or other lubricating-material, by means of an opening leading from the outside of the wheel into the reservoir *A*, as indicated by the dotted lines *5*. After the desired quantity of the lubricating-material is put in the reservoir, this opening, if so desired, may be closed by a suitable plug, or other means. Now, the revolving of the wheel will cause the lubricating-material to flow across the face *6* of the projection *O*, and thereby cause a very small portion of the lubricating-material to flow into the opening *3*, and through it into the chamber *n* of the opening *B* for the axle, which will thereby be kept properly lubricated without loss or waste of the lubricating-matter. It will be observed that the lubricating-matter will alternately flow from the reservoir *A* into the chamber *n*, and from chamber *n* into reservoir *A*, and will thus, by the revolving of the wheel and flowing of oil from one chamber to the other, give out only the necessary supply of the lubricating-matter to keep the wheel and its axle properly lubricated.

Having thus described the nature, construction, and operation of my improvement, what I claim as of my invention is—

The reservoir *A*, provided with projection *O*, furnished with an opening, *3*, for communicating between the reservoir *A*, chamber *n*, and opening *B* for the axle, the whole being constructed, arranged, and operating substantially as herein described, and for the purpose set forth.

W. W. MARTIN.
